CLOCK

Charles A. McLeod, Oak Park, Ill., assignor to Sunbeam Corporation, Chicago, Ill., a corporation of Illinois

Filed Oct. 10, 1966, Ser. No. 4,215

Term of patent 14 years

(Cl. D42—7)

FIG. 1 is a front elevational view of a clock embodying my new design;

FIG. 2 is a top plan view thereof; and

FIG. 3 is a sectional view taken substantially along line 3—3 of FIG. 1.

It is understood that the wheat pattern shown fragmentarily at the top and two bottom corners is continuous about the entire portion of the molding.

I claim:

The ornamental design for a clock, as shown and described.
